UNITED STATES PATENT OFFICE.

WILLIAM JOHN MOON, OF BRISTOL, ENGLAND.

DESIGN FOR A SWEETMEAT-RECEPACLE.

No. 38,315.

Specification for Design.

Patented Nov. 20, 1906.

Application filed March 20, 1906. Serial No. 307,177. Term of patent 7 years.

To all whom it may concern:

Be it known that I, WILLIAM JOHN MOON, a subject of the King of Great Britain and Ireland, residing at Temple Back, Bristol, in the county of Gloucester, England, have invented a new, original, and ornamental Design for a Sweetmeat-Receptacle, of which the following is a specification, reference being had to the accompanying drawing, forming part thereof, which drawing is a perspec-

tive view of a receptacle provided according to my design.

I claim—

The ornamental design for a sweetmeat-receptacle as shown.

WILLIAM JOHN MOON.
